TOOLHOLDER

Lewis J. Stibits, Philadelphia, Pa.

Application April 25, 1946, Serial No. 664,873

7 Claims. (Cl. 77—59)

(Granted under the act of March 3, 1883, as
amended April 30, 1928; 370 O. G. 757)

1

This invention relates to an adjustable drill-holder.

More specifically this invention relates to a holder for a portable pneumatic or other type drill that enables the operator to drill accurately at an angle, particularly in drilling packing-plunger holders for watertight doors and hatches.

An object of this invention is to provide a drill-holder that will allow accurate drilling at an angle.

Another object is to provide a drill-holder that is simple to operate, is adjustable readily, and guides the drill with accuracy.

Further objects and advantages of this invention, as well as its construction, arrangement and operation, will be apparent from the following description and claims in connection with the accompanying drawing, in which

Fig. 1 is a side elevational view of a drill-holder in operating position, the drill being shown in phantom lines; and

Fig. 2 is a partial view in vertical cross-section, similar to Fig. 1, showing a positioning member, a boss, and a drill guide bushing.

Fig. 1 shows a preferred embodiment of the invention wherein drill-fixture 10 is shown in operating position and secured to the work, in this case door 11, which has holes 13 therein and bosses 31 integral therewith. The threaded positioning-member or plug 12 passing through one of holes 13 is mounted removably to door 11 by means of nut 14.

The positioning-member 12 has a shoulder 33 and a top 39 in the general shape of a frustum of a cone.

The upper portion of the shaft 12 has arm 15 extending horizontally and arm 17 extending vertically therefrom. Arm 15, integral with shaft 12, has at its extremity integral lug 34 and bolt 16. Vertical arm 17 is mounted rotatably upon the upper surface of shaft 12 by bolt 33, which passes through lug 37 integral with shaft 12. Arm 17 is bifurcated to permit rod 18 to pass therethrough. Rod 18 is attached rotatably to horizontal arm 15 by bolt 16. Locating holes or perforations 19 in arm 17 and rod 18 are adapted to fix the angle of drill 20. Bolt 32 passing through holes 19 secures rod 18 to arm 17.

Mounted slidably on rod 18 are drill-holders 21 and 22 with set-screws 23 provided thereon in order to permit positioning of drill 20. Drill-holder 21 has recess 24 therein to permit the insertion of drill handle 25. Drill-holder 22 has adjustable arm 26 received therein and secured by set-screw 27. Arm 26 has a bore 28 which

receives threaded drill guide or bushing 29, which is held in place by set-screw 30.

It can be seen from the above that when boss 31 is to be drilled, the fixture 10 is secured to the door 11 by means of lock-nut 14 in such a position as to place tool-holders 21 and 22 and boss 31 in the same vertical plane. A limited choice of vertical angular adjustment is obtainable by matching holes 19 in rod 18 and arm 17 and securing these members by bolt 32.

By placing the drill 20 between the holders 21 and 22, inserting handle 25 in recess 24 of drill-holder 21, the drill 20 is held firmly in place. The drill-bit 35 of drill 20 is inserted in the bushing 29. In the operation of the invention, the drill-bit 35 is progressed forward by turning the internally threaded handle 25 to permit drilling of bore 36.

Various modifications and changes can be made in the subject device without departing from the scope of the invention.

The invention described herein may be manufactured and used by or for the Government of the United States of America for governmental purposes without the payment of any royalties thereon or therefor.

I claim:

1. A tool-holder comprising a support, means to secure said support to the work, a first arm fixed to said support, a second arm mounted rotatably on said support, an elongated guide-rod, said guide-rod being mounted rotatably on said first arm, said guide-rod and said second arm having perforations, a bolt passing through a perforation in said second arm and said guide-rod, tool-holders mounted slidably on said guide-rod, means to secure said tool-holders on said guide-rod, one of said tool-holders having a third arm mounted slidably therein, and a guide bushing in said third arm.

2. A drill-holder comprising a generally cylindrical support, said support having a threaded end, a mid portion and a shoulder above said mid portion, a top portion above said shoulder, a first arm generally normal to said support and integral with said top portion, a lug at the outer extremity of said first arm, a guide-rod pivoted to said lug, said support having a second lug integral therewith, a second arm mounted rotatably on said second lug, said second arm having perforations, a bolt extending through a perforation of said second arm and said guide-rod, a drill-holder mounted slidably on said guide-rod near the free end thereof, a second drill-holder mounted slidably at an intermediate position on

said guide-rod, said second drill-holder having an extension generally normal to said guide-rod, a third arm mounted slidably in said extension and a drill-guide bushing received threaded by said third arm, said drill-holders being adapted to clamp a drill therebetween.

3. A drill-holder comprising a first arm adapted to be secured to a workpiece at an angle thereto, a first plurality of spaced locating holes in said first arm, a second arm mounted on said first arm and extending at an angle thereto, a rod mounted on said second arm distal said first arm and rotatable in the plane of said first and second arm, a second plurality of spaced locating holes in said rod adapted to be aligned with corresponding locating holes in said first arm, means to secure a selected hole of said first plurality of holes to a selected hole of said second plurality of holes, and means to secure a drill in axial parallelism with said rod.

4. A drill-holder comprising a first arm adapted to be secured to a workpiece at an angle thereto, a first plurality of spaced locating holes in said arm, a second arm mounted on said first arm and extending at an angle thereto, a rod mounted on said second arm distal said first arm and rotatable in the plane of said first and second arms, a second plurality of spaced locating holes in said rod adapted to be aligned with correspondingly locating holes in said first arm, means to secure a selected hole of said first plurality of holes to a selected hole of said second plurality of holes, and means to secure a drill upon said rod beyond the juncture of said rod and said second arm in axial parallelism with said rod.

5. A drill-holder comprising a first arm adapted to be secured to a workpiece at an angle thereto, a first plurality of spaced locating holes in said arm, a second arm mounted on said first arm and extending at an angle thereto, a rod mounted on said second arm distal said first arm and rotatable in the plane of said first and second arms, a second plurality of spaced locating holes in said rod adapted to be aligned with corresponding locating holes in said first arm, means to secure a selected hole of said first plurality of holes to a selected hole of said second plurality of holes, and a plurality of lugs mounted slidably upon said rod beyond the juncture of said rod and said first arm, said lugs being

adapted to secure a drill in axial parallelism with said rod.

6. A drill-holder comprising a first arm adapted to be secured to a workpiece at an angle thereto, a first plurality of spaced locating holes in said arm, a second arm mounted on said first arm and extending at an angle thereto, a rod mounted on said second arm distal said first arm and rotatable in the plane of said first and second arms, a second plurality of spaced locating holes in said rod adapted to be aligned with corresponding locating holes in said first arm, means to secure said rod to said first arm at selected holes of said rod and said first arm, and means to secure a drill upon said rod beyond the juncture of said rod and said first arm, said means including means to vary the angular disposition of such drill relative said rod.

7. A drill-holder comprising a first arm adapted to be secured to a workpiece at an angle thereto, a first plurality of spaced locating holes in said arm, a second arm mounted on said first arm and extending at an angle to said first arm, a rod mounted on said second arm distal said first arm and rotatable in the plane of said first and second arms, a second plurality of spaced locating holes in said rod adapted to be aligned with corresponding locating holes in said first arm, means to secure a selected hole of said first plurality of holes to a selected hole of said second plurality of holes, and a plurality of lugs mounted slidably upon said rod beyond the juncture of said rod and said first arm, at least one of said lugs having an arm mounted slidably therein, whereby the angular disposition of such drill relative said rod can be varied.
